UNITED STATES PATENT OFFICE.

KARL KIEFER, OF CINCINNATI, OHIO.

FILLING-MACHINE.

1,115,834.

Specification of Letters Patent.

Patented Nov. 3, 1914.

Application filed October 19, 1908. Serial No. 458,492.

To all whom it may concern:

Be it known that I, KARL KIEFER, a citizen of the United States, and resident of Cincinnati, in the county of Hamilton and State of Ohio, have invented certain new and useful Improvements in Filling-Machines, of which the following is a specification.

The object of my invention is to simplify the construction and increase the durability of filling machines, and to add to the convenience of operation thereof.

My invention consists in the details of construction and arrangement hereinafter more fully set forth and claimed.

In the drawings: Figure 1 is a side elevation of a machine embodying my invention. Fig. 2 is a cross-sectional elevation of part of the filling head. Fig. 3 is a front elevation of the same. Fig. 4 is a detail perspective view of part of one of the filling tubes. Fig. 5 is a plan view of the complete apparatus shown in Fig. 1.

As illustrated herein, a top 1 and a base 2 hold four standards 3 in fixed upright parallel relation, and a bracket 4 is rigidly secured to these standards, at the proper height. The bracket 4 has a forward extension in which a screw rod 5 slides up and down, being raised or lowered by the hand wheel 6 threaded on the screw rod above said forward extension of the bracket 4. The upper end of this screw rod 5 carries the table 7, and the table 7 has lugs sliding on the forward two of the standards 3. This table receives the bottles to be filled, and by its vertical adjustment accommodates the machine to bottles of different heights. A frame 8 is guided vertically by said two forward standards, through the medium of wheels or rollers 9 and 10 which bear on the rear sides and the front sides, respectively, of said front standards. The front wheels 10 are larger, and there are grooves or tracks for them in the standards, in which the wheels roll, preventing lateral displacement of the frame 8. This frame carries the filling head, forwardly of its roller 10, over the table 7, which filling head will be described in detail later.

The lower end of the frame 8 is free to swing forwardly or rearwardly of the machine, by virtue of the naturally slight looseness of the bearing of the rollers 9 and 10 on the standards. This slight swinging

movement permits a radius rod 11, fulcrumed at its rear end on a pin 12 in a block 13 on the base 2, to have its forward end directly pivoted to this lower end of the frame 8, and thereby be utilized to impart up and down movement to the frame 8 and to the filling head carried thereby. It is readily seen that the slight amount of swinging imparted to the frame 8 by the action of this radius rod thereon, will be inappreciable at the upper end of the frame 8, where the filling head is carried, because this upper end is so close to the rollers 9 and 10, which become the fulcrums of this slight swinging movement. Thus, the construction is greatly simplified, yet thoroughly practical.

A link 14 is pivoted to the radius rod 11 near the lower end of the frame 8, and this link 14 is also pivoted to the shorter member of the bell-crank lever 15, fulcrumed on the tapered shoulder 21^a, as is best seen in ards 3.

The filling head comprises filling tubes with means to engage with the bottle-tops, and has springs 16 to govern the action of such engagement. Naturally, the springs increase their resistance to compression the more they are compressed, so that, ordinarily, where a plurality of tubes with their springs are to be operated simultaneously, by manual effort, the operation of the machine is unduly laborious, owing to the highly increased resistance of the springs during the latter period of their compression. I have improved the mechanism so that the mechanical advantage of the actuating parts increases as the resistance of the springs increases, thereby combining the requisite speed of operation with relief from excessive effort on the part of the operator. This I accomplish by the combination of the simple bell-crank lever 15 and the link 14 with the proper connection to the filling head, in this case comprising the radius rod 11 and the frame 8 which carries the filling head. Inspection of Fig. 1 will enable this combination to be readily understood. As shown by the full lines, the short arm of the lever 15 is in a nearly horizontal position, with the link 14 at about right-angles to it. Now, when the long member of the lever 15 is pulled forward and downward by the operator, the parts will move into positions indicated by the dotted lines, wherein the short arm of the lever 15 engages with a

10^a

100

10^b

110

stop pin 36 in the bracket 4, preventing further depression. It will be noticed that the pivotal connection of the upper end of the link 14 with the short arm of the bell-crank 5 lever 15 is then somewhat to the rear of a straight line through the fulcrum of the lever and the pivotal connection of the other end of the link with the radius rod 11. Thus, the action of the springs 16 now, on 10 account of the passing of the link and lever-arm over the center line, is to hold the parts in this position.

From the foregoing description, it will be seen that when the start of the compression 15 is made, with the lever-arm nearly at right-angles to the link, considerable speed is attendant upon the action of the lever on the filling head, through the connections; but as the lever-arm descends, this speed lessens 20 and the mechanical advantage correspondingly rises. Thus, as the lever-arm and the link approach alinement, the power of the operator over the springs is increased many fold, until, when alinement is reached, the 25 springs are completely overcome, and the power required of the operator to resist them is *nil*. Then, further movement of the lever downward carries the parts over the center line, as above referred to, holding the 30 parts down during the filling operation. The release is easily effected by raising the lever until the lever-arm and the link pass back over their alinement.

A weight 17 is mounted on an arm 35 tending rearwardly from the fulcrum of the bell-crank lever, substantially in alinement diametrically with the short arm of the lever, and adapted to swing with the lever on said fulcrum. The weight may be ad- 40 justed along this arm, so that it has the proper counterbalancing effect on the parts above described. The action of this weight 17 is also such as to compensate the increased resistance of the springs 16. Thus, 45 as the weight rises, during the descent of the other parts, its counterbalancing effect grows less, on account of its passing up over the fulcrum. This will be readily understood from inspection of Fig. 1, where the 50 weight in its raised position is indicated by dotted lines.

Each filling tube comprises an inner tube 18, which is, by means of a suitable bushing which it has at its upper end, screwed into 55 a lateral extension of the tubular reservoir 19. This tubular reservoir lies across the machine, being supported near its ends in the upper terminations of the side members of the frame 8, before described. One end 60 of this reservoir is closed, and the other end has a nipple to receive a hose or pipe, through which the substance to be filled into the bottles is supplied to the machine. The extensions of the reservoir 19, which receive 65 the tubes 18 as above described, are arranged

in diametrically opposite series on the reservoir, in a horizontal plane. Lateral passages lead out from the interior of the reservoir, in these lateral extensions, and thus communicate with the interiors of said tubes 70 18. All the tubes are vertical, in conformity with the principle of operation of the machine, which is to depress the tubes vertically into the bottles or other vessels held on the table 7. This combination of the 75 tubular reservoir with the vertically disposed tubes supplied through lateral extensions of the reservoir is novel, and in advance of the usually employed tanks, with tubes projecting from their bottoms. The 80 reservoir 19 affords sufficient reserve capacity for preserving the uniform action of the machine in filling, but at the same time it is compact and light, thereby adding to the ease of use of the apparatus. Each filling 85 tube also has a sleeve 20 surrounding the lower region of the tube 18, and this tube 18 has an enlargement 21 at its lower end, sliding inside the sleeve 20, and carrying a valve-seat or gasket 22, on which the lower 90 end of the sleeve 20 finds an annular seat, limiting its downward movement and closing the slight annular leakage space around the enlargement 21 inside the sleeve 20, due to the sliding fit that these parts have to 95 each other. To guide the enlargement 21 into the sleeve 20, this enlargement has a tapered shoulder 21^a, as is best seen in Fig. 4.

The upper end of the sleeve 20 is secured 100 in a movable head 23, and it is between this movable head 23, and the bushing of the tube 18 that the spiral spring 16 is compressed. The interior of this movable head 23 is hollow, and the annular space around the tube 18, inside the sleeve 20, forms a vent passage communicating with this hollow interior. An overflow spout 24 leads from this hollow interior of the head, and the upper end of the head is open around the 110 tube 18, to allow escape of air independently of the overflow spout 24. The enlargement 21 has a lateral orifice that forms the lower outlet of the tube 18.

A bell 25, slidable with respect to the 115 sleeve 20, is positioned so as to receive the bottle-top in its tapering interior, to guide said bottle-top so as to receive the tube, and to bring said bottle-top in engagement with an annular, inwardly conical gasket 26, 120 inside the bell. Thus, as the tube enters the bottle, an air and liquid tight connection is made between the bottle and the bell 25. This bell is fixed to the lower ends of the stiff guide-rods 27, which flank the tube 18, 125 and the sleeve 20 and its head 23, and lie parallel to them. The upper ends of these rods are held in fixed parallel relation by a yoke 28, and the rods are guided, near their upper ends, by sliding in lateral lugs 29 on 130

the extension of the reservoir that receives the tube 18. The yoke 23 has cushioned engagement with the upper side of the extension, limiting the downward movement of 5 the rods 27 and the bell thereon.

An overflow trough 30 lies between the opposite series of tubes, below the reservoir 19, and receives the overflow from the spouts 24, conducting it laterally of the machine 10 to a suitable outlet.

The guide-rods 27 have lower bearings in lateral lugs 31 on the overflow trough 30. The reservoir 19 and the trough 30 both being rigid castings, firmly supported by the 15 frame 8, it will be seen that the guide rods are firmly guided, and they thus carry the bell 25 so as to prevent its transmitting any impact to the necessarily somewhat delicate tube and sleeve.

20 When the descent of the bell 25 is stopped by the engagement of its gasket 26 with the bottle top, the outer tube 20 and the movable head 23 will continue to be carried downward by the filling head and the tube 25 20 will be inserted into the bottle. Continuing downward, the head 23 will engage its gasket 32 with the top of the bell 25, and then the downward movement of the tube 20 will stop, but the inner tube 18 will then 25 be pushed down out of the outer tube 20, with the spring 16 yielding, and will thus unseat the lower end of the sleeve from the seat 22 and then uncover the enlargement 21 and its lateral orifice. This opens the 30 tube 18 for flow of liquid from the reservoir into the bottle, and also opens the lower end of the sleeve 20, for venting of air from the bottle, and for overflow after this lower open end of the sleeve 20 has become sub- 35 merged by the liquid rising in the bottle. It will thus be seen that the filling height is determined by the distance which this sleeve projects into the bottle. Its projection is dependent upon the position of the gasket 40 45 22, with which the bell 25 must engage, not only to complete the air and liquid tight closure of the bottle with the filling tube and its sleeve, but also to cause the sleeve to rise on the tube and permit the flow of 50 liquid to start. For the purpose of adjusting the position of this gasket 32, it is mounted on a cup 33 fitting up around the lower end of the head 23, and around the sleeve 20. This cup may be moved up or 55 down on the head, and has a set screw 34 that may engage in any one of a vertical series of depressions in the surface of the head. Thus, the filling height in the bottles may be regulated.

60 The spring 16, if allowed to bear directly on the sleeve 20, will deflect or twist it and the tube 18, during the changes in stress on the spring in operating the machine. Therefore, I provide the head 23 with wings 35, 65 through which the guide rods 27 pass,

whereby the head is guided on these rods so firmly as not to be influenced by any detrimental action of the spring 16, which bears against it. This eliminates nearly all the tendency of the sleeve to deflect with 70 respect to the tube; but to provide for such slight deflection as may occur, I taper the upper end of the enlargement 21, so that it will enter the sleeve 20 freely when the sleeve descends on withdrawal of the bottle. 75

It will be seen that the bell 25, approaching the lower bearings 31 of the guide-rods 27, derives increased stability as the resistance of the spring 16 increases.

Since only the guide-rods need lubrication, it is possible to avoid all danger of contact of the lubricant with the liquid being filled.

By firmly guiding the bottle-centering devices and the sleeves, and by providing a 85 compensating lever mechanism for applying the tubes to the bottles, improvement is effected in that class of machines requiring effective gasket connection between the tube and the bottle, in rendering them more certain and less laborious in operation. This relieves the operator of excessive physical exertion, and also of necessity of extreme care in operation of the machine.

Having fully described my invention, 95 what I claim as new and desire to secure by Letters Patent is:

1. In a filling machine, a tubular reservoir, diametrically opposite series of extensions thereon, corresponding series of parallel filling tubes in the extensions, the filling tubes of each series being parallel to those of the other, an overflow trough lying under the reservoir between the opposite series of tubes, means co-acting with the tubes and supporting means for said co-acting means, said co-acting means and said supporting means being slideable with respect to said tubes and parallel therewith, liquid-conducting means from said supporting means to the trough, and guiding means on said reservoir and on said trough for said co-acting means and its supporting means.

2. In a filling machine, a reservoir, a filling tube fixed therein, a sleeve, a head on the sleeve, vessel-guiding means slideable along the sleeve, a guide-rod fixed to the vessel-guiding means parallel with the sleeve, bearings for the guide rod, and an extension on said head bearing on the guide rod, whereby the head and sleeve are slideable along the guide-rod and guided thereby.

3. In a filling machine, a reservoir, a lateral extension thereon, a tube fixed in the extension, a sleeve slideable with respect to the tube, a head on the sleeve, vessel guiding means slideable along the sleeve, guide-rods fixed to the vessel-guiding means, flanking said sleeve and said tube and parallel with them, bearings for said guide-

- rods in the extension on the reservoir, extensions on said head bearing on said guide-rods and slidable thereon, and a spiral spring between said head and said extension on the reservoir, surrounding the tube.
4. In a filling machine, a tube, a sleeve inclosing an annular vent passage around the tube, a head in which the sleeve is fixed and with which it slides with respect to the tube, bottle-engaging means slidable with respect to the sleeve and the tube, and means on said head, adjustable longitudinally of said sleeve, for the bottle-engaging means to engage with.
- 15 5. In a filling machine, a tube, a sleeve around the tube, a head in which the sleeve is fixed and with which it slides with respect to the tube, bottle-engaging means slidable with respect to the sleeve and the tube, a cup extending up around said head and surrounding said sleeve, and adjustable longitudinally thereof, and means for holding said cup stationary on said head in various adjusted positions, said bottle-engaging 20 means engaging with the lower side of said cup.
6. In a filling machine, movable bottle-engaging means, a spring to yieldably resist movement of the bottle engaging means, 25 supporting means for the bottle-engaging means and its spring, compressible, and compressing said spring on depression, a bell-crank lever, and connection from said lever to said compressible supporting means comprising a link connected to an arm of said lever and lying at a substantial angle to said arm before depression of said supporting means, but approaching alinement with said arm as the supporting means is depressed and said spring compressed.
- 30 7. In a filling machine, movable bottle-engaging means, a spring to yieldably resist movement of the bottle-engaging means, supporting means for the bottle-engaging means and its spring, compressible, and compressing said spring on depression, a bell-crank lever, and connecting means from said lever to said compressible supporting means, comprising a link connected to an 35 arm of said lever, a weight diametrically opposed to said arm of the lever and moving therewith, said link lying at a substantial angle with said arm, and said weight being disposed substantially horizontally 40 from said arm, before depression of said supporting means, but said link approaching alinement with said arm, and said weight rising over said arm as the supporting means is depressed and said spring compressed.
- 45 8. In a filling machine, movable bottle-engaging means, a spring to yieldably resist movement of the bottle-engaging means, supporting means for the bottle-engaging means and its spring, compressible, and com-

pressing said spring on depression, a lever, and means connecting said lever to said compressible supporting means to depress said means, and to compensate the varying resistance of said spring as it is compressed 70 during said depression.

9. In a filling machine, movable bottle-engaging means, a spring to yieldably resist movement of the bottle-engaging means, supporting means for the bottle-engaging means and its spring, compressible, and compressing said spring on depression, a lever to depress said supporting means and a weight to counterbalance said lever and supporting means, said lever and said weight 80 having connection with said supporting means whereby they compensate the varying resistance of said spring.

10. In a filling machine, movable bottle-engaging means, a spring to yieldably resist movement of the bottle-engaging means, supporting means for the bottle-engaging means and its spring, compressible, and compressing said spring on depression, a lever, a link, and connection of said link to said 85 supporting means, said lever and said link being adapted to become aligned during depression of said supporting means, and to pass over their alinement to complete said depression, whereby they tend to maintain 90 said supporting means in depressed position.

11. In a filling machine, a tube, a sleeve around the tube, and bottle-engaging means, said sleeve and said bottle-engaging means being severally movable and said sleeve having means for engagement of the bottle-engaging means, supporting means for said tube, sleeve and bottle-engaging means, a lever, and connection from said lever to said supporting means, whereby the supporting 100 means is depressed with relative rapidity during the approach of the bottle-engaging means to said engaging means on the sleeve, but is depressed more slowly after said engagement.

12. In a filling machine, a filling head comprising severally movable operative elements, one of which is stopped by engagement of the other, a lever, and means connecting said lever to said filling head, to 105 depress said filling head with decreasing rapidity.

13. In a filling machine, a filling head, a frame to carry said filling head on one end, a fulcrum for said frame, near said filling head, allowing vertical movement of the frame and the head, and a radius rod connected to the other end of the frame, remote from the fulcrum, whereby vertical operative movement is imparted to the frame and head, accompanied by a slight swinging movement which in the region of said head is negligible.

14. In a filling machine, a filling tube with an enlargement near one end, a lateral 130

orifice through said enlargement and an overflow tube surrounding the filling tube and leaving an annular space therearound and therealong, said space and said orifice being closed when the overflow tube covers the enlargement but opened when said overflow tube uncovers said enlargement, there

being a tapered shoulder on said enlargement to guide the overflow tube when it covers the enlargement.
